UNITED STATES PATENT OFFICE.

CONRAD ROBICHAUX, EDWARD DAIGLE, AND DANIEL WEBRE, OF RACELAND,
LOUISIANA.

SACK FUNNEL.

Application filed July 2, 1925. Serial No. 41,108.

The invention relates to sack funnels, for holding sacks during a filling operation, and has for its object to provide a device of this character provided with means for piercing and holding the upper end of the sack in open position during a sack filling operation, and with tripping means for the sack holding means whereby the sack may be quickly released when full. Also to provide means whereby the funnel may be suspended from a weighing device, thereby allowing a predetermined quantity of material to be placed in the sack, and obviating the necessity of weighing the sacks after they have been filled as is the practice at the present time.

A further object is to provide the opposite sides of the funnel adjacent the lower end thereof with rock shafts having their ends provided with outwardly and upwardly inclined prongs for piercing opposite sides of a sack and spring means for normally maintaining the rock shaft in a position where its prongs will incline upwardly and outwardly. The rock shafts are provided with upwardly and outwardly inclined arms which are held against downward movement under the weight of a sack suspended on the prongs by means of pivoted hooks cooperating with the arms. Also to provide a rock shaft having a handle member and arms cooperating with the pivoted hook whereby the rock shaft arms may be simultaneously released for allowing disengagement of the sack from the prongs under the weight of the material within the sack.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a side elevation of the funnel.

Figure 2 is an enlarged bottom plan view of the funnel.

Figure 3 is a detail sectional view taken on line 3—3 of Figure 1.

Referring to the drawing, the numeral 1 designates a tapered funnel, the lower end of which is of sufficient width to be received within the upper end 2 of a bag or sack. Extending upwardly from the funnel 1 is a

bail 3, by means of which the funnel may be supported from a support, or from weighing scales, whereby the amount of material discharged into the sack 2 through the funnel 1 may be accurately determined, consequently sacks of uniform weight are filled. Rockably mounted in bearings 4 at opposite sides of the discharge opening 5 are rock shafts 6. The ends of the shaft 6 are provided with upwardly and outwardly inclined prongs 7 adapted to pierce opposite sides of the sack 2 and support the opened end of the sack over the lower end of the funnel, whereby material deposited in the funnel will be deposited in the sack. Surrounding the rock shafts 6 are coiled springs 8, one of the ends of which are anchored at 9 to the sides of the funnel and the other ends of the springs are anchored at 10 to upwardly and outwardly extending arms 11 of the rock shafts. It will be seen that the springs 8 will normally force the arms 11 upwardly, however the springs 8 are not of sufficient tension to support a sack full of material, therefore it will be seen that when a sack has been filled, and the arms 11 released by tripping mechanism hereinafter set forth, the weight of the sack on the prongs 7 will cause the rock shaft 6 to rotate against the action of the coiled springs 8, thereby automatically disengaging the sack from the funnel after a filling operation.

Pivoted mounted at 12 in recesses 13 at the opposite sides of the funnel 1 are outwardly extending latching members 14, which latching members hook over the outer ends 15 of the arms 11, and hold said arms adjacent the sides of the funnel with the piercing members 7 inclining upwardly and outwardly, therefore it will be seen that the sack 2 will be positively connected to the funnel during the sack filling operation, and said sack will be immediately released upon an upward movement of the latching members 14, however when the arms 11 are moved upwardly after a sack releasing operation, the ends 15 of the arms 11 engage the inclined surfaces 16 of the latches and force the same upwardly until the ends 15 of the arms 11 are received in the recesses 17 of the latches. Rockably mounted in bearings 18 at one side of the funnel is a rock shaft 19, the ends of which rock shaft are provided with angularly disposed arms 20 at opposite sides of the funnel, and which arms have

link connections 21 with the latching members 14. When the operator desires to release the sack 2, he grasps the handle member 22 of the rock shaft 19 and forces the 5 same downwardly, which action will move the arms 20 carried by the shaft 19 upwardly, and which arms will impart upward pulls on the latching members 24, through the medium of the link connections 21, thereby releasing the arms 11 and allowing the sack and the weight of the material therein to rock the rock shafts 6 against the action of the coiled springs 8.

From the above it will be seen that a sack 15 filling funnel is provided which is simple in construction, positive in its operation and one wherein the parts are reduced to a minimum, thereby allowing the device to be cheaply constructed and sold.

20 The invention having been set forth what is claimed as new and useful is:—

A sack holding funnel comprising a body member, one end of which is adapted to be received within an open end of a sack, rock-

able members at opposite sides of the body 25 member, sack piercing arms carried by the ends of the rockable member, upwardly and outwardly extending arms carried by the rockable members, springs surrounding the rockable members and cooperating with the 30 body member and said upwardly and outwardly extending arms for normally forcing said arms inwardly, pivoted latches at opposite sides of the body member and cooperating with the upwardly and outwardly 35 extending arms, a rock shaft carried by one side of the body member, arms carried by the ends of the rock shaft and overlying the adjacent sides of the body member, link connections between said last named arms 40 and the latching members, and a handle member carried by said rock shaft.

In testimony whereof we have signed our names to this specification.
